(57) **CLAIM**

The ornamental design for an incubation bag, as shown and described.

DESCRIPTION

FIG. 1 is a top-front perspective view of an incubation bag showing my design;

FIG. 2 is a front elevational view of the incubation bag of FIG. 1;

FIG. 3 is a rear elevational view of the incubation bag of FIG. 1;

FIG. 4 is a right-side elevational view of the incubation bag of FIG. 1;

FIG. 5 is a left-side elevational view of the incubation bag of FIG. 1;

FIG. 6 is a top plan view of the incubation bag of FIG. 1;

FIG. 7 is a bottom plan view of the incubation bag of FIG. 1; and,

FIG. 8 is a top-front perspective view of the incubation bag of FIG. 1, shown with a front end of the incubation bag in an open configuration.
